[57] CLAIM

The ornamental design for a cannister, substantially as
shown and described.

DESCRIPTION

FIG. 1 is a top, front, right side perspective view of a
cannister showing my new design;

FIG. 2 is an exploded perspective view thereof;

FIG. 3 is an exploded bottom, front, right side perspec-
tive view thereof;

FIG. 4 is a top plan view thereof;

FIG. 5 is a bottom plan view of the lid shown separately
for clarity of illustration;

FIG. 6 is a left side elevation thereof;

FIG. 7 is a top plan view of the lower portion of the
cannister shown separately for clarity of illustration;
and

FIG. 8 is a cross section taken along line 8—8 in FIG. 6.
